UNITED STATES PATENT OFFICE.

SCHOOLER C. HORN, OF BLADENSBURG, OHIO.

IRONING-BOARD.

SPECIFICATION forming part of Letters Patent No. 483,922, dated October 4, 1892.

Application filed March 31, 1892. Serial No. 427,273. (No model.)

To all whom it may concern:

Be it known that I, SCHOOLER C. HORN, a citizen of the United States, residing at Bladensburg, in the county of Knox and State of 5 Ohio, have invented a new and useful Ironing-Board, of which the following is a specification.

This invention relates to ironing-boards adapted for ironing shirts, and also skirts and 10 analogous articles; and it consists in the construction and arrangement of the parts thereof, as will be more fully hereinafter described and claimed.

The object of this invention is to provide 15 convenient appliances in connection with an ironing-board whereby the neckband may be properly distended and the lower portion of the bosom fastened to produce the requisite tension and place a shirt in such position as 20 to remove wrinkles and make the process of ironing more readily accomplished.

In the drawings, Figure 1 is a perspective view of an ironing-board in position to receive a shirt and to expand or distend the 25 neckband and stretch the bosom thereof. Fig. 2 is a top plan view of the same. Fig. 3 is a longitudinal vertical section thereof. Fig. 4 is a cross-section on line xx , Fig. 2.

Similar numerals of reference indicate 30 corresponding parts in the several views.

Referring to the drawings, the numeral 1 designates the board proper, having reversible legs 2, pivotally connected to one end thereof and held in either of their adjusted positions 35 by stops 3. The board is reversible, one side thereof being adapted for employment as an ordinary ironing-board and may be suitably padded, as is ordinarily done. The opposite side of the board at one end thereof is provided with a bosom-board 4, which is secured in position permanently and is shaped to conform to the bosom of a shirt. Across the lower end of said board 4 is a cleat or strip 5, of less thickness than the said board, and acts 40 as a stop for mechanism, which will be herein-after set forth. Adjacent to this lower end of the bosom-board 4 is mounted a stretcher, which consists of a fixed section 6, to which is connected a movable section 7. The said 45 movable section 7 has pins 8 secured thereto and surrounded by coiled springs 9, said pins and coiled springs being movably seated in

openings in the ends of the fixed section 6. The outward movement of the movable section 7 is limited by the cleat or strip 5, against 55 which it normally bears, and the said movable section is also formed with a groove 11 extending entirely across the same.

To the fixed section 6 is pivotally connected a bail 12, having eyes 13, and in said eyes are 60 secured the ends of a clamping-bail 14, which is adapted to take over the movable section 7 and engage the groove 11 thereof. The bail 12 forms an operating-bail for the clamping-bail 14, and when arranged in the position 65 shown in Fig. 3 it is thrown back of the fixed section 6.

On the head end of the board 4 is mounted a neckband-expanding device, which consists of two semicircular blocks 15 and 16, the block 70 15 being fixed and the block 16 movable. The block 16 has a guide-bar 17, secured thereto, said guide-bar having a dovetailed portion 18, moving through a dovetailed slot 19 in the fixed section 15. The said portion 75 18 of the bar 17 is provided with a series of teeth or pins 20, projecting from the upper face thereof and above the surface of the fixed section 15. A lever 21 is pivoted to the section 15, as at 22, on opposite sides of the inner 80 termination of the dovetailed slot 19. A loop 23 is secured to the lever and extends beyond the same a suitable distance, in order to engage the teeth or pins 20, projecting upward from the bar 17, as set forth, to thereby 85 draw the section 16 toward the section 15 or force the same outward therefrom in order to release the same from contact with the neckband or to retain the neckband in position therearound. The upper surface of the bar 90 17 in section 16 is provided with notches 24 to operate the section before pressure of the lever 21 is required. At the head of both boards a screw-rod 25 is inserted and passes through a slot 26 in the upper edge of a clamping-block 27, the said clamping-block having a wire loop spanning the said slot 26 to hold the block rotatably on the said screw-rod. A clamping-arm 28 is fitted to the screw-rod 25 and is adapted to force the block 27 close 95 against the head end of the board. The said block 27 is formed with a shoulder 29, upon which the board 1 rests when the bosom-board 100 is in position for use, the said shoulder being

wide enough to permit the block 27 to be moved away from the board a suitable distance to insert a portion of the shirt being clamped thereby without withdrawing the shoulder entirely from beneath the board. This shoulder 29 forms a wall 30, which is curved to conform to the curve of the adjacent ends of the boards, and therein are held the shoulder portions of the shirt when the latter is clamped in position on the bosom-board.

When the device is used for ordinary ironing, the clamping-arm 28 is loosened on the screw-rod 25, and the clamping-block may be reversed, so that the shoulder 29 will take against the bosom-board 4, and the legs 2 are reversed when the board proper (designated by the numeral 1) will be in position for use.

In applying a shirt to the bosom-board it is properly fitted thereover and the shoulder portions held by the clamping-block 27. The neckband is placed around the neckband-expanding device, consisting of the sections 15 and 16, and the said section 16 is operated to expand the same. The lower portion of the shirt is drawn down over the stretcher, the bails 12 and 14 having been first thrown backward. The bails are then moved forward until the clamping-bail 14 takes over the movable section 7 into the groove thereof, which draws the lower portion of the shirt therewith, and the bail 12 is then thrown back of the fixed section 6, thereby firmly holding and stretching the shirt-bosom in position.

The convenience and advantages of the construction hereinbefore set forth are readily apparent to those skilled in the art, and need not be further enlarged upon herein.

It will be apparent that the section 15 of the neck-block could be made movable in a manner similar to the section 16 and the lever and its parts be arranged to reversely operate to what is shown in the drawings. This change in the parts would involve no departure from the invention, and, in fact, could be obtained by a mere reversal or turning around of the parts as now positioned.

Having thus described the invention, what is claimed as new is—

1. In an ironing-board, the combination of 50 a board proper and a bosom-board fixed to one side thereof and having a screw-rod projecting from the end of the same, a reversible clamp at the end of said boards having a recess in the upper side thereof and a wire loop 55 for the passage therethrough of the said screw-rod, and also provided with a shoulder on which the board rests, a collar-expander on the bosom-board, and a stretching device at the foot of the bosom-board, substantially 50 as described.

2. In an ironing-board, the combination of 55 a board proper and a bosom-board fixed to one side thereof, a stretcher consisting of a fixed section, a movable section, an operating-bail pivotally connected to said fixed section, and a clamping-bail movably attached to said operating-bail and adapted to engage the said movable section, substantially as described.

3. In an ironing-board, the combination of 70 a board proper and a bosom-board thereon, a neckband-expanding device consisting of a fixed section and a movable section, a guide-rod having projections thereon and secured to said movable section, and a lever attached 75 to the fixed section and having a loop adapted to engage said projections of the guide-rod, substantially as described.

4. In an ironing-board, the combination of 80 a board proper and a bosom-board fixed thereon, a stretcher consisting of a fixed and a movable section arranged at the foot of said bosom-board, an operating-bail pivotally connected to said fixed section, a clamping-bail 85 movably attached to said operating-bail, a neckband-expanding device at the head of said bosom-board, consisting of a movable and a fixed section, and a reversible clamp at the head of said boards having a shoulder, substantially as described.

In testimony that I claim the foregoing as my own I have hereto affixed my signature in the presence of two witnesses.

SCHOOLER C. HORN.
